UNITED STATES PATENT OFFICE

168,346

RAILWAY CAR BODY

Ralph W. Haman, Flossmoor, Alfred B. Girardy, Park Forest, and Clarence V. Norby, Chicago, Ill., assignors to Pullman-Standard Car Manufacturing Company, Chicago, Ill., a corporation of Delaware

Application March 29, 1952, Serial No. 19,116

Term of patent 14 years

(Cl. D66—1)

To all whom it may concern:

Be it known that we, Ralph W. Haman, Alfred B. Girardy, and Clarence V. Norby, citizens of the United States of America and residents, respectively, of Flossmoor, county of Cook and State of Illinois, Park Forest, county of Cook and State of Illinois, and Chicago, county of Cook and State of Illinois, have invented a new, original, and ornamental Design for a Railway Car Body, of which the following is a specification, reference being had to the accompanying drawings, forming part thereof.

In the drawings:

Fig. 1 is a general perspective view of a conventional railway car body in which our new design is incorporated, having portions broken away better to reveal the disposition of the dining section within the vehicle, and showing the supporting trucks in dotted lines;

Fig. 2 is a horizontal mid-sectional view taken through the vehicle showing the dining section;

Fig. 3 is a vertical longitudinal sectional view through the vehicle showing the dining section, taken on the line 3—3 of Fig. 2;

Fig. 4 is a vertical transverse sectional view through the vehicle showing the dining section, taken on the line 4—4 of Fig. 2.

Fig. 5 is a vertical transverse sectional view through the dining section, taken on the line 5—5 of Fig. 2; and

Fig. 6 is a general perspective view of the dining section in the railway car body.

The characteristic features of the present design reside in the interior dining section design shown in the drawing.

What is claimed is:

The ornamental design for a railway car body, substantially as shown and described.

RALPH W. HAMAN.

ALFRED B. GIRARDY.

CLARENCE V. NORBY.
